REGENERATIVE COKE OVEN AND THE LIKE

Joseph van Ackeren, Pittsburgh, Pa., assignor, by
mesne assignments, to Koppers Company, a
corporation of Delaware

Application June 12, 1935, Serial No. 26,169

12 Claims. (Cl. 202—143)

My invention comprehends improvements in regenerative coke ovens and relates more particularly to improvements in the regenerator system of such coke ovens and the like. The invention 5 has for an object a new and useful method of controlling the distribution and flow of gases in the heating channels and conduits of regenerative heating arrangements such as are incorporated in coking retorts, by-product coke ovens 10 and the like; and pertains especially to modifications in the design and functioning of sole-channels, their arrangement and method of operation, which effect automatically a uniform distribution and length of travel for all gases entering such 15 channels before and when they are delivered to the flame flues and thence discharged into the waste-heat tunnel.

In regenerative coking ovens which comprise horizontally elongated chambers that are separated each from the other by their heating walls, 20 within which are arranged a plurality of vertical heating flues disposed from one end of the oven to the other, and in which the heating gases are burned, or along which the products of combustion 25 are carried away toward the stack, the air participating in the combustion or, in the case where the ovens are of the combination type and the heating medium is produced extraneously and is of low heat content, both the air and the 30 heating gases are separately preheated by passing them over hot checker-bricks before they are introduced into the flame or combustion flues. These checker-bricks are brought to the desired 35 temperature, before the air and the gas are passed over them, by the passing of the hot products of a combustion process which has previously taken place at another point in the oven's heating system.

The checker-bricks are arranged in a suitable 40 space therefor beneath the oven, forming the regenerator. The regenerators are usually so disposed that their longitudinal axes lie parallel with those of their associated ovens, and are in this manner arranged contiguously along the 45 length of the battery. The design of the regenerators used in the various types of ovens and the arrangement of the checker-bricks used as the media for the storage of heat, depend upon the principles of gaseous flow and combustion around 50 which the oven is constructed and operated. The regenerator space beneath an oven may be divided longitudinally or transversely or both, into two or more sections, and each section may function in a different capacity at any particular 55 stage of operation according to design.

Uniform distribution of the gases flowing through the regenerators is one of the prime requisites for their efficient utilization. Regardless, however, of the principles used in their design and method of operation, they all depend upon a sole-flue or bus-channel of some type to uniformly apportion and assemble the gases passing through them to or from all parts of the checker-brick work. For this purpose, after their introduction through the battery walls by 10 means of suitable valves or ports the gases to be distributed travel along the sole-flues, whence they discharge through a series of laterally disposed canals or ducts into the checker-brick of the regenerator lying either below or above. The 15 volume of gas that passes from a particular duct depends upon its relative size and the static pressure in the carried gas. The gaseous distribution thus effected will so continue in the heating system through the region beyond the sole-flues, if throughout that region only uniform 20 pressures are encountered during the transit. If, however, in the system inequalities of resistance are met during such transit, the uniform distribution will be disturbed and means must be taken 25 either to redistribute the gases or to eliminate conditions creating the inequalities in resistance.

In the regenerative heating of an oven, the following cycle is quite typical. The air or 30 the gas to be used for combustion is passed into a sole-flue channel through a port or suitably designed box. After distribution through lateral orifices along the sole-flue channel, these gases pass over previously heated checker-brick where 35 they are preheated before introduction into the series of vertical combustion flues situated between the oven walls. The air and gas for heating are mixed at the base of the flues where combustion gradually takes place during their ascent 40 and a portion of their heat is transferred through the heating walls to the coal beyond. From the combustion flues, the still extremely hot waste-gases pass into a similar series of flues in the opposite or same wall of the oven, continually losing 45 some of their remaining heat content; following which, they then flow into a second regenerator, which having been traversed, they flow together in a sole-flue channel after passing through ducts laterally disposed along the axis 50 of the sole-flue. Within the second regenerator a major portion of the heat still remaining in the combustion gases after they have left the oven walls, is absorbed by the checker-brick, before they enter the sole-flues whence they pass to a 55

common waste-heat tunnel, the stack and eventually to the atmosphere. At the predetermined intervals the flow of gases in a regenerative heating system is reversed and the second regenerator in the former partial cycle, during which interval it has been reheated to proper temperature, now becomes the first regenerator in the reversed cycle of flow, the former waste-heat flues become the combustion flues and the regenerator which previously was preheating air or gas is now recovering the heat remaining in the combustion gases which has passed between the oven's heating walls unabsorbed.

From this brief description of a regenerative heating cycle, it is readily apparent that the sole-flue orifices of a regenerative system at one interval in the cycle are functioning to distribute heating gases uniformly throughout the checker-brick space, and during the second interval are serving to collect or assemble uniformly into the associated sole-flue, the combustion gases flowing into it from all parts of a regenerator.

In those instances therefore where, during a complete regenerative cycle the direction of the flow of the gases is completely reversed in the sole-flue as is the case where in consequence of the taper of the ovens it is desirable to isolate the complete heating system of the pusher side of the oven from the coke side because of the differences in quantity of coal to be coked during the same time interval, or where the heating gases of an oven wall are reversed on either side of a reversal plane perpendicular to the longitudinal axis of the oven, the same sole-flue at one interval of the heating cycle is being used to effect uniform distribution of gases to a regenerative space and at a later interval to effect uniform withdrawing of gases from that same space and in a contra-directional flow. Heating systems involving the above-described principle have a tendency upon reversal to direct the flow of gases into channels different from those through which gases had been previously flowing, and attempts to correct this tendency by means of sliding brick for dampering purposes at either end of the vertical heating flues during one direction of gaseous flow, serve only to accentuate such tendency to irregular distribution during the reverse flow, with the resultant effect that gases entering the regenerators for preheating purposes assume a tendency to traverse different zones in the regenerators from those through which the combustion gases passed during the period when the regenerators were being reheated.

This phenomenon results from Bernoulli's theorem which demonstrates that the total pressure found in any channel through which a fluid is flowing comprises a velocity pressure and a static pressure. At any point in such channel, the sum total of these two pressures is equal (neglecting friction), so that, obviously wherever the velocity and its resultant pressure is the highest the static pressure is the lowest and vice versa. Since the static pressure is the only force which causes the fluid to flow from any orifice or duct opening from that channel perpendicular to the direction of flow, it becomes evident that if the velocity of the gas in the channel is not uniform, the static pressure will vary accordingly and consequently, also the volume of gas discharged from adjacent orifices if they are of unidimensional proportions.

The gases entering a sole-flue for distribution have their greatest velocity head at some point near the inlet port and as they discharge through

the ducts in the sole-flue arch, the velocity gradually decreases to zero at the end of the flue, where the highest static pressure will be found. Consequently, the greatest volume of gases is discharged from the sole-flue ducts nearest the sealed end, if the gases are flowing into a region of constant pressure.

During the period of reverse flow, when gases are passing from the regenerator into the sole-flue to be discharged into the waste-heat canal, the velocity of the gases increases in the sole-flue from a point near the closed end to the outlet port. The static pressure at the orifices leading into the sole-flue consequently decreases progressively in the same direction, offering progressively less resistance to the inflow of gases from the regenerator as the waste-gas outlet port is approached. The result of this phenomenon is to cause a channeling across the regenerator space in the direction of those sole-flue ducts nearest the waste-heat port and create the tendency for the gases leaving the regenerator to assume a different path from that taken by the gases introduced into the regenerator during the reversed period of flow as aforementioned.

Calibration of the sole-flue ducts in such manner as to accommodate increasing static pressure when gas is flowing into the sole-flue from the gas or air supply lines and permit uniform volumes of gas to flow into the various parts of the regenerator therefrom, will, during flow in the reverse direction through the sole flue in the next regenerative reversal period, only further increase the tendency of the gases to flow into those ducts nearest the waste-heat outlet port.

In my present invention, I therefore provide means whereby the aforementioned undesirable distribution effects may be simply and effectively circumvented while simultaneously effecting a simplification in thermal control of coking retorts, ovens and other regenerative heating systems, as well as a reduction in number of the more complex control accessories used to regulate the flow of fuel gases in such a system. A uniform distribution of air or gas, absorption of heat and flow of the products of combustion will be accomplished automatically. The invention has for further objects such other improvements and such other operative advantages or results as may be found to obtain in the processes or apparatus hereinafter described or claimed.

Briefly stated, my invention provides that during the regenerative heating cycle of an oven, the movement of gases in all regenerator sole-flues have the same direction of flow and that this same direction of flow be maintained during the reversal period of the regenerative heating cycle.

My invention further provides, in combination with a uni-directional flow of the gases in the sole-flues of an oven at all times, a calculated and proper gradation in the size of the ducts connecting the regenerator sole-flues with the regenerator checker-brick, which is based on recognition of the increasing static pressure in the gaseous stream effected by its reduction in volume as it flows from the inlet port of the regenerator sole-flues toward the closed end and also upon the decreasing static pressure which takes place in the regenerator sole-flues effected by the increasing volume of the gas stream as it flows from the closed end of the sole-flue toward the discharge port; the decrease and increase in volumes of the gas stream being effected respectively by the distribution of gases to the heat-

ing flues from the sole-flues or their confluence in the same after combustion.

The general advantages of my invention will be more easily understood by reference to the accompanying drawings forming a part of this specification and showing for the purposes of exemplification an apparatus in which the invention may be embodied and practised but without limiting the claimed invention specifically to such 10 illustrative instance or instances.

In the drawings,

Figure 1 is a vertical sectional view taken longitudinally through a coke oven. The sections shown are taken on the lines A—A and B—B 15 respectively of Figure 2.

Figure 2 is a transverse vertical section through a coke oven battery and is taken on lines II—II of Figure 1.

Figure 3 is a horizontal sectional view of the 20 sole-flues of a coke oven battery, the same being taken through the lines III—III of Figure 1 and showing somewhat diagrammatically the graduation of the orifices along the sole-flues.

Figures 4, 5, 6 are views of waste-heat, gas 25 and air, and air valves respectively as employed in practising the present invention.

Figure 7 is an elevational end view of the 30 various types of valves shown in Figures 4, 5 and 6 in operating position and illustrates their arrangement sequence as used in practising the present invention; and

Figure 8 is a view as in Figure 3 but with an alternative system of sole-channel orifices.

In the drawings the same characters of 35 reference designate the same parts in all of the views of the drawings.

Referring now to the drawings, Figures 1 and 2, show for the purposes of exemplification an oven of the well known cross-over type of Joseph 40 Becker U. S. Patents No. 1,374,546 and No. 1,904,191 and more particularly an improvement in that type exemplified in a Joseph Becker pending application Serial No. 2,564, wherein my 45 invention may be embodied and practised and which for purposes of the following exposition will be treated as a combination oven, the heat for the underfiring of which is derived from the combustion of a gas of low heating value extraneously produced, and requiring preheating prior to 50 its introduction into the combustion zone.

In a coking retort battery comprising a series of horizontally elongated ovens of this type so disposed that their longitudinal axes are parallel, the individual ovens are separated one from the 55 other by a series of vertically disposed heating flues extending from one end of each oven to the other, each series serving to heat adjacent walls of contiguous ovens. The heating flues are communicably connected at their lower ends with regenerator spaces lying beneath and at their 60 upper ends with cross-over flues which pass over the top of the oven and connect with the vertical heating flues of the oven's opposite wall at their upper ends. Each cross-over flue may serve any 65 preferred number of vertical flues and for this purpose the flues in any wall are arranged in a series of sets which communicate by means of the cross-overs with a set of similar number in the opposite wall of the oven.

The vertical heating flues between the two adjacent walls of contiguous ovens communicate 70 with two regenerators beneath each, extending longitudinally parallel to the oven's walls and the coking chambers, and the regenerators are separated throughout their entire length, one from

the other by the supporting pillar walls of the ovens. Each vertical flue is provided with a communicating opening to each of the underlying regenerators. For operating purposes the regenerators are disposed in groups of four, two regenerators of each group being intercommunicably connected with the other two through the heating flues, the cross-overs and the ducts at the lower end of the vertical flues.

In the base of each regenerator lies a regenerator sole-flue which, through ducts laterally disposed along its lengthwise dimension, communicates with the regenerator checker-brick, and at one end with the atmosphere or source of heating medium supply and at the other with the waste-heat tunnel. The sole-flues are continuous of the 10 entire length of the regenerator, which makes possible the introduction of air and gas for combustion of an entire oven wall at one side of the 15 battery only.

The reversal plane in the regenerative heating cycle lies substantially parallel to the oven walls along a median line longitudinally bisecting an oven.

In the operation of my invention in a coking 20 retort battery of the above-described type, the coal to be subjected to the distillation process is introduced into an oven 1, through suitable 25 openings 2 at the top of the oven. Gas and air to be burned in the flues 3, which for the moment 30 are the flame flues, are simultaneously introduced into the air and gas regenerator sole-flue channels 4 and 5 respectively by opening the air valve 6 and the gas valve 7 at one end of the oven. Just prior to the opening of these valves, 35 the valves 8 and 9 at the opposing ends of the sole-flues 4 and 5 respectively and at the opposite end of the oven, have been closed. These 40 valves are operated by the movement of a reversing mechanism (not shown), which motion is translated to them by cable 10. The air and gas 45 enter sole-flue channels 4 and 5 respectively at a preferred total pressure head, which, as these gases flow along said sole-flues separated by the oven supporting pillar walls 11, remains substantially 50 the same (save for friction), but the relation of the component pressures comprising the total pressure, changes. Such change results, as hereinbefore indicated, from the constantly decreasing velocity of the air and gas in the sole-flues as they flow from the valves 6 and 7 toward 55 their opposing end at valves 8 and 9 (Figure 7), in consequence of the outflow of the gas and air through the ducts 12 in the sole-flue rider-brick as they pass upward into the regenerator checker-brick spaces 13 and 14.

The constant decrease in the velocity of the 60 gases and the attendant decrease in velocity pressure requires a like increase in the static component of the total pressure, when substantially the same total gas pressure is maintained along the entire length of the sole-channel. The out-flow of the gases from their respective sole-channels 12 into the regenerators above is by occasion of the static pressure. Obviously, then, 65 if a uniform distribution of the gases to the various parts of an associated regenerator space is to be effected by the sole-flue ducts, means must be provided to counteract the effect of this constant static pressure increase along the sole-flue. In 70 the present invention, I provide such means by so dimensioning the cross sectional area of the sole-flue ducts 12 that at the static pressure existing at any point in the sole-flue, the volume of gas allowed to flow through adjacent ducts is equal 75

in volume to that allowed to pass through the ducts adjacent any other point in the sole-flue. Since the static pressure progressively increases from the air or gas introducing end (as at valves 6 and 7) toward the closed end of the flue (as at valves 8 and 9), these ducts shall constantly decrease in cross sectional area as the closed end is approached by gases flowing from the open end.

The air or gas, uniformly distributed through out the entire associated regenerator spaces 13 and 14 by the graduated ducts of the sole-flues, is preheated and flows upward respectively through ducts 21 and 28 leading into the bottom of flame or combustion flues 3, where they mix and gradually burn as they ascend to collect in the discontinuous horizontal flue 18, whence by means of the cross-over conduit 17, the products of the aforementioned combustion flow across the top of the oven and downward into the heating flues along the opposite oven side, (as indicated by the arrows in Figure 2). Continuing in their downward flow, the waste gases pass through ducts 21' and 28' into the regenerators W. H., where a major portion of their remaining heat content is absorbed by the checker-brick before they flow through the communicating ducts 12 into the sole-flues beneath.

As the combustion products much reduced in temperature pass into the sole-flues to be discharged into the atmosphere after flowing through valves 8' and 9' (Figure 7), the waste-heat flue 18 and the stack (not shown), their volume and velocity continually increase as they gather in the sole-flue and flow toward the discharge end. As aforescribed, this increasing velocity brings about a decreasing static pressure in the sole-flue as the discharge end is approached, and this decreasing static pressure, offering less resistance to the inflow of the waste products of combustion, gives rise to a tendency for these products to flow in greater volume through those ducts below which the lowest static pressure exists. Uniform volume of gas flow through these ducts is therefore, in my invention, obtained by so decreasing their cross sectional area in the direction of flow of the gases in the sole-flue that at the static pressures existing below each, a substantially equal volume of gases will pass through all individual ducts from the checker-brick to the sole-flue beneath.

By thus properly graduating the ducts 12 so that the changing static pressures along the sole-flues are compensated for, and adapting the sole-flue for uni-directional flow in the proper direction during both inflow and outflow, it is apparent to those skilled in the art that uniform gaseous distribution throughout all parts of the regenerators will be effected.

During the period of reverse flow in the regenerative heating cycle, when the flues 3 instead of being the flame flues, carry away the products of combustion through the regenerators G and A (Figure 2) which formerly introduced gas and air into flues 3 from the sole-flues 5, 4 but now function to carry away the combustion products, it is necessary to maintain the same relationship of sole-flue duct cross sectional area to static pressure that existed in the previous period, if uniform distribution is to be maintained. Consequently, in the practice of my invention, I provide in a complete regenerative heating cycle for the introduction of gas and air at but one end of the oven, and alternately on either side of the flow reversal plane, while the products of combustion pass from the oven structure at the

opposite end, alternately on either side of the same reversal plane, the in-flow of the heating media and out-flow of their waste combustion products taking place always on opposing sides of the flow reversal plane during both periods of the heating cycle. In this manner, the direction of gaseous flow in the regenerator sole-flues will always be toward sole-flue ducts of decreasing cross sectional area and a setting once established therein will be similarly effective during both "on" and "off" periods of the heating cycle.

Referring now to Figures 3 and 8, by means of which the gaseous flow through the heating system of a single oven may be more simply understood. Gas and air are respectively introduced into the sole-flues 5, 4 through valves at 7, 6 as shown, and flowing along these channels are uniformly apportioned by the ducts 12 into their respective regenerators 14 and 13 along their entire length as they flow toward the closed valves at 9, 8. As the gases rise through the regenerators 14 and 13 and enter the flame flues 3 through communicating conduits 28, 27, they mix and burn, passing through the cross-over flues 17 into the heating flues, the regenerators 25 and sole-flues on the opposite side of the flow reversal plane, and leave the heating system at the open valves 8' and 9' (W. H.) and pass into the waste-heat flue 18. During the interval of reverse flow, valves at 6, 7, 8' and 9' are closed and valves at 6' and 7' open for the introduction of air and gas into the system, and the valves at 8, 9 are opened to allow withdrawal of the waste gases. Reversal of flow of the gases in the heating flues and regenerators has been effected but the same direction of gaseous flow in the regenerator sole-flues has been maintained.

In the practice of my invention a uniform length of flow for all gases entering the heating system of an oven is assured. Gas and air entering the regenerators at point C, in Figures 1 and 3, will be burned in the heating flues 3 directly above and pass by means of the cross-over conduit into the regenerator sole-flues on the opposite side of the flow reversal plane at a point C' and continue the full length of said sole-flues before being discharged at 8' and 9', whereas gas or air which enters the regenerators at some such point as D will have traversed the full length of the sole-flues 5 and 4 before it enters the regenerators, is burned in the flame flues directly above and passes into the regenerator sole-flues on the opposite side of the reversal plane at D' directly adjacent the valves at 8' and 9' where the combustion products pass into the waste-heat flue.

In the operation of my invention, I prefer to introduce the fuel gases into the sole-flues of adjacent ovens on opposing sides of the battery (as shown in Figure 3) as an added assistance in obtaining uniformity of heat distribution and in limiting the size of gas mains and waste-heat tunnels.

With the invention of this system of effecting and maintaining uniform gaseous distribution in the heating system of an oven, which makes possible introduction of the heating media to any oven at one side of the battery only, the requirements of the more expensive combination air and gas valves used when underfiring with producer or blast furnace gas are reduced to one-half those formerly needed, the remainder may be replaced by valves of simpler design. This results in a reduction in the capital out-lay required for an installation.

The regenerators are so disposed as to operate in groups of four, as shown in Figure 2, and those regenerators which pre-heat gas for combustion along the walls of an oven lie in juxtaposition between air regenerators which thereby function to isolate the gas from the waste-heat regenerators, to safeguard against leakage and loss or firing of gas that might be drawn from a gas into a waste-heat regenerator by the pressure differential that exists between them. The air and gas having uni-directional flow in their respective regenerators, there is substantially little or no pressure differential between them. A group of gas and air regenerators comprising two of each alternate with a group of four waste-heat regenerators along the lengthwise axis of the battery, which relationship obtains through both periods of a complete heating cycle.

If it is preferred to underfire the battery or a portion thereof with rich gas such as is produced in the carbonization process itself, the conversion is simply effected by closing the communicating connection between the lean gas main 19, in Figure 5, and its associated regenerator, at valve 20, and removing lever arm 21 controlling valve 7 from actuating contact with the reversing cable 10. Since rich gas requires larger amounts of air per unit volume to effect complete combustion, air is now introduced into the regenerator, which formerly carried lean gas to the heating flues, and through the valve 22 of the combination gas and air box. Following this adjustment, rich gas carried in the mains 23 extending along both sides of the battery is introduced by proper adjustment of the valves 24 into the gas conduits 25 situated in the head of the oven supporting pillar walls 11a. From the conduits 25, the rich gas passes upward through ducts 26 into the vertical flues where it is admixed and burned with air rising through the regenerators 13 and 14.

The graduation of the regenerator sole-flue ducts may be variously practised without departing from the intent of my invention. Depending upon the nature of the apparatus or the design of the structure within which it is desirable to embody my improvement, the details of its application may vary. In certain instances of conditions and circumstances, the afore-described changes in static pressure along the sole-flue may be of such magnitude as to give expediency to progressive graduation of each duct; that is, in the direction of gaseous flow each duct will be smaller than the one immediately preceding. In other cases, however, static pressure change may alter at such a moderate rate that the ducts may be divided into groups for graduation purposes. In this modification of my invention then, the amount of graduation required by the change of static pressure within certain zone limits may be averaged, for example, and the so-derived average cross sectional area applied to ducts within that zone. This application has its practical aspect more especially in those cases where the fabrication media do not lend themselves to such small progressive differentiations in duct size as the theoretical considerations would impose.

In Figure 8 is shown a special instance of such group-wise duct graduation. In this exemplification the sole-channel ducts of each regenerator are divided into four groups designated by letters E, F, G and H respectively, from the gas or air introducing end toward the combustion products

discharging end. In this drawing it will be seen that the first eleven ducts comprising the group E at the heating media inlet end are all of uniform cross section; in the following group F comprising another group of eleven ducts, the cross sectional area of each duct comprising the group is the same, but of somewhat smaller area than the ducts comprising group E; in the last two groups G and H comprising 6 and 5 ducts respectively, the cross section of the ducts becomes 10 group-wise smaller, but the ducts in any group remain ungraduated.

As an example, but without limiting myself to such illustrative instance, the proportional difference of area between the different groups may 15 be as follows:

Group E comprising ducts 3 $\frac{1}{2}$ sq. in. in area.
Group F comprising ducts 3 $\frac{1}{2}$ sq. in. in area.
Group G comprising ducts 3 sq. in. in area.
Group H comprising ducts 2 $\frac{1}{2}$ sq. in. in area. 20

At points (X) on the drawings are shown breaks in the regularity of the duct disposal along the sole-channel, such hiatus in the disposal indicates points where regenerator cross walls may be incorporated in the structure if preferred, as an assistance toward maintaining the uniform distribution in the checkerbrick affected by the graduated sole-channel ducts. 25

In the hereinabove described application of my 30 invention, wherein reference is made to its use in a coke oven battery, in alternate sets of regenerators the heating gases have been introduced into the sole-flues at opposite sides of the battery.

My invention is, however, not limited to such 35 arrangement. When available space or other conditions permit or make it desirable my improvement allows the heating media to be introduced into all the regenerators from one side of the battery only, and the products of combustion 40 to be withdrawn from the opposite side; one waste heat tunnel, therefore, on one side of the battery may serve the entire installation and one gas main on the opposite side will serve for supplying the entire heating gas requirements, thereby 45 effecting obvious desirable structural and mechanical simplifications.

The invention as hereinabove set forth is embodied in particular form and manner but may be variously embodied within the scope of the 50 claims hereinafter made.

I claim:—

1. In a regenerative coke oven comprising a horizontally elongated chamber with walls comprising vertical heating flues communicably connected at their lower ends with regenerators having horizontally disposed sole-flues at their base extending parallel to the oven walls continuously from one end of the oven to the other, with regulable means for supplying gas and air to and closing the sole-flues thereto at their one end and regulable means for establishing and severing communicable connection with a waste-heat tunnel at their other end, calibrated communicating openings between the sole-flues and the regenerators graduated in such manner that the openings increase in cross-sectional area from the waste-heat discharging end to the gas or air supplying end of the sole-flues. 55

2. In a reversible regenerative coking retort 70 oven having, means for gas firing the same and at least four regenerators disposed to operate in pairs alternately on either side of a flow reversal plane substantially paralleling the oven walls and adapted to operate in alternation with each 75

- other to convey air to and the waste products of combustion from the heating flues, means for introducing the air alternately on either side of the flow reversal plane at but one end of the oven and into sole-flues beneath the regenerators, means for alternately on either side of the flow reversal plane withdrawing the products of combustion from the sole-flues at the opposite end of the oven, closable inlet means at one end of the respective sole-flues for inflow thereto from the means for introducing and closable outlet means at the opposite ends of the respective sole-flues for outflow therefrom to the means for withdrawing, the inlet means and outlet means for each sole-flue being operable in alternation with each other, the improvement characterized by the graduation of the communicating openings between the sole-flues and the regenerators in decreasing cross-sectional area from a point adjacent the inlet end of the sole-flues toward the opposite end, so that the flow of gases in the sole-flues on both sides of the reversal plane during both inflow and outflow will be always toward lateral sole-flue openings of decreasing cross-sectional area.
3. In a battery comprising a series of reversible regenerative coking ovens substantially as described in claim 2, and in which means for introducing the heating media are disposed at the opposite ends of contiguous ovens.
4. In a reversible regenerative coking retort oven of the combination type having, means for gas firing the same and at least four regenerators disposed to operate in pairs alternately on either side of a flow reversal plane substantially paralleling the oven walls and the pairs adapted to convey the heating media to and the waste products of combustion from the heating flues in alternation with each other, means for introducing the heating media alternately on either side of the flow reversal plane at but one end of the oven and into sole-flues beneath the regenerators, means for alternately on either side of the flow reversal plane withdrawing the products of combustion from the sole-flues at the opposite end of the oven from which the heating media is adapted to be introduced, means for alternately opening one end of the respective sole-flues to the means for introducing while closing the opposite end of the same to the means for withdrawing and for closing said one end of the respective sole-flues to the means for introducing while opening the opposite end of the same to the means for withdrawing, the improvement characterized by the communicating openings between the sole-flues and the regenerators being graduated in decreasing cross-sectional area from a point adjacent the inlet end of the sole-flues toward the combustion products outlet end, so that the flow of gases in the sole-flues on both sides of the reversal plane will be always toward lateral sole-flue openings of decreasing cross-sectional area.
5. In a cross regenerative coking retort oven battery of the combination type having means for gas firing the same and comprising, in combination, a plurality of ovens each served by at least four regenerators disposed to operate in pairs alternately on either side of a flow reversal plane substantially paralleling the oven walls and the pairs adapted to convey the heating media to and the products of combustion from the heating flues in alternation with each other, the regenerators for the inflow of heating gas to the walls of any oven being laterally adjacent and separated from the regenerators for the out-flow of the products of combustion by a regenerator for in-flowing air, means for introducing the heating media to the respective pairs alternately on either side of the flow reversal plane and at but one end of the oven and into sole-flues beneath the regenerators, means for withdrawing the products of combustion from the sole-flues of the respective pairs of regenerators of a group alternately on either side of the flow reversal plane at the opposite end of the oven, means

for alternately opening one end of the respective sole-flues to the means for introducing while closing the opposite end of the same to the means for withdrawing and for closing said one end of the respective sole-flues to the means for introducing while opening the opposite end of the same to the means for withdrawing, the improvement characterized by the arrangement of the communicating openings between the sole-flues and the regenerators into groups of orifices, all orifices within a group having substantially the same cross-section, but the orifices of each succeeding group decreasing in cross-section from a point adjacent the inlet end of the sole-flues toward the combustion products outlet end, so that the flow of gases in the sole-flues on both sides of the reversal plane will be always toward lateral sole-flue groups of orifices of decreasing cross-section.

11. In a reversible regenerative coking retort oven having, means for gas firing the same and two sets of regenerators disposed for operation with their flow reversal planes substantially paralleling the oven walls and adapted to operate in alternation with each other to convey combustion media to and the waste products of combustion from the heating flues, means for introducing the combustion media alternately on either side of the flow reversal planes at but one end 30 of the oven and into sole-flues beneath the regenerators, means for alternately on either side of the flow reversal plane withdrawing the products of combustion from the sole-flues at the opposite end of the oven, closable inlet means at one end of the respective sole-flues for inflow thereto from the means for introducing and closable outlet means at the opposite ends of the respective sole-flues for outflow therefrom to the means for withdrawing, the inlet means and outlet means for each sole-flue being operable in alternation with each other, the improvement characterized by the graduation of the communicating openings between the sole-flues and the regenerators in decreasing cross-sectional area from a point adjacent the inlet end of the

sole-flues toward the opposite end, so that the flow of gases in the sole-flues on both sides of the reversal plane during both inflow and outflow will be always toward lateral sole flue openings of decreasing cross-sectional area. 5

12. In a reversible regenerative coking retort oven having, vertical combustion flues in the oven walls with each of the flues in each of the heating walls communicably connected at their upper parts with vertical flues in another of the heating walls at their upper parts for flow of waste gas to and from each other in alternation by cross over ducts crossing over intervening coking chambers, means for gas firing the same and two sets of regenerators disposed for operation with their flow reversal planes substantially paralleling the oven walls and adapted to operate in alternation with each other to convey combustion media to and the waste products of combustion from the heating flues, means for introducing the combustion media alternately on either side of the flow reversal plane at but one end of and into sole-flues beneath the regenerators, means for alternately on either side of the flow reversal plane withdrawing the products of combustion 25 from the sole-flues at but the opposite end of the sole-flues, closable inlet means at one end of the respective sole-flues for inflow thereto from the means for introducing and closable outlet means at the opposite ends of the respective sole-flues 30 for outflow therefrom to the means for withdrawing, the inlet means and outlet means for each sole-flue being operable in alternation with each other, the improvement characterized by the graduation of the communicating openings between the sole-flues and the regenerators in decreasing cross-sectional area from a point adjacent the inlet end of the sole-flues toward the opposite end, so that the flow of gases in the sole-flues on both sides of the reversal plane 40 during both inflow and outflow will be always toward lateral sole-flue openings of decreasing cross-sectional area. 35
